US00D843442S

(12) United States Design Patent (10) Patent No.: US D843,442 S
Barlier et al. (45) Date of Patent: * Mar. 19, 2019

(54) TYPE FONT(71) Applicant: Apple Inc., Cupertino, CA (US)(72) Inventors: Guillaume P. Barlier, San Mateo, CA (US); Alan C. Dye, San Francisco, CA (US); Aurelio Guzmán, San Jose, CA (US); Nicolas V. Scapel, Sunnyvale, CA (US); Christopher Wilson, San Francisco, CA (US)(73) Assignee: Apple Inc., Cupertino, CA (US)() Term: 15 Years(21) Appl. No.: 29/616,905(22) Filed: Sep. 10, 2017(51) LOC (11) Cl. 18-03

(52) U.S. Cl.

USPC ..... D18/33; D18/27(58) Field of Classification Search
